United States Patent Office

Des. 200,014
Patented Jan. 5, 1965

200,014

JUG

Albert B. Mojonnier, 5357 NE. River Road, Chicago, Ill.,
and John S. Frazer, 2-04 Kenneth Ave., Fair Lawn,
N.J., assignors of one-half to Albert Mojonnier, Inc.,
Franklin Park, Ill., a corporation of Illinois

Filed July 2, 1964, Ser. No. 80,684

Term of patent 14 years

(Cl. D58—5)

Fig. 2.

Fig. 1.

Fig. 3.

Fig. 4.

FIG. 1 is a side elevational view of one side of a jug embodying our new design, the other side being a mirror image thereof;

FIG. 2 is a front elevational view thereof;

FIG. 3 is a top plan view thereof; and

FIG. 4 is a rear elevational view thereof.

The dominant features of our design reside in the portions in full lines.

We claim:

The ornamental design for a jug, substantially as shown and described.
